His Attorney.

UNITED STATES PATENT OFFICE.

OTTO F. PERSSON, OF ERIE, PENNSYLVANIA, ASSIGNOR TO GENERAL ELECTRIC COMPANY, A CORPORATION OF NEW YORK.

AIR STARTING MEANS FOR INTERNAL-COMBUSTION ENGINES.

1,298,557.

Specification of Letters Patent. Patented Mar. 25, 1919.

Application filed September 13, 1918. Serial No. 253,998.

To all whom it may concern:

Be it known that I, Otto F. Persson, a citizen of the United States, residing at Erie, in the county of Erie, State of Pennsylvania, have invented certain new and useful Improvements in Air Starting Means for Internal-Combustion Engines, of which the following is a specification.

The present invention relates to air starting means for internal combustion engines and has for its object to provide an improved construction and arrangement in a mechanism of this character.

For a consideration of what I believe to be novel and my invention, attention is directed to the accompanying specification and claims appended hereto.

In the drawing, the figure is a diagrammatic view of a structure embodying my invention.

Referring to the drawing, 5 indicates the cylinder and 6 the piston of an internal combustion engine. In the head of the cylinder is arranged an air starting valve 7 which opens inwardly and is normally held closed by a spring 8 located between a head 9 on the outer end of valve stem 10 and valve easing 11. Compressed air for starting the engine is admitted to valve easing 11 through a passage 12 with which connects a pipe 13 which leads to a controlling valve 14 provided with an operating handle 14^a. Valve 14 is arranged to connect pipe 13 to a pipe 15 which leads from a suitable supply of compressed air (not shown) or to atmosphere by way of opening 16. The head 9 on valve stem 10 is pivotally connected by a link 17 to one end of a lever 18, the other end of which is connected to an actuating rod 19 which terminates adjacent a cam shaft 20 and which has on its end a roller 21 adapted to be engaged by a cam 22 on cam shaft 20. Cam shaft 20 is operated from the crank shaft of the engine in any suitable manner. Lever 18 is fulcrumed on a block 23 which is in the form of a piston and is located in a cylinder 24 carried on the engine cylinder head. Piston 23 is adapted to move in cylinder 24 to bring the roller 21 into and out of operative relation to cam 22. A spring 25 normally holds the piston 23 in a position such that the roller 21 does not lie in the path of movement of cam 22. Connected to the upper end of cylinder 24 is a pipe 26 which leads from the compressed air pipe 13

and whenever air is admitted to pipe 13 to start the engine it also passes by way of pipe 26 to cylinder 24 and forces piston 23 downward to bring roller 21 into operative relation to cam 22. 27 is a packing to prevent leakage past piston 23, and 28 and 29 are shoulders which form stops to limit the movements of piston 23.

In the drawing, the controlling valve 14 is shown in such position that pipe 13 is not connected to pipe 15. Spring 25 holds piston 23 against stop shoulder 29 thus maintaining roller 21 out of the path of cam 22. This is the inoperative position. If now it is desired to start the engine, operating handle 14^a is moved from the inoperative position to the starting position which results in connecting pipe 15 to pipe 13. The compressed starting air then flows through passage 12 to the valve 7 and also through pipe 26 to cylinder 24 where it acts on piston 23 to force the same downward and bring roller 21 into the path of cam 22 where it will be held during the starting operation. The engine will have been previously adjusted so that cam 22 is in the position shown in the drawing or it will be now adjusted to such position which results in valve 7 being opened and a charge of starting air admitted to the cylinder 5. The engine will thus be started in the well understood manner, the cam 22 periodically opening the starting valve 7 to admit successive charges of starting air to the cylinder. After the engine is started operating handle 14^a is moved back to inoperative position cutting off communication between pipes 13 and 15 and connecting pipe 13 to vent opening 16. The pressure above piston 23 is thus quickly relieved to atmosphere and spring 25 moves piston 23 up against stop shoulder 29 which results in moving roller 21 out of the path of cam 22.

With the above described arrangement it will be seen that in bringing the roller 21 into the path of cam 22 I move the fulcrum of lever 18 and that none of the parts entering into this operation forms a part of the elements which are moved by cam 22 in opening valve 7. The weight of the parts moved by cam 22 are thus reduced to a minimum and hence offer the least amount of inertia.

In accordance with the provisions of the patent statutes, I have described the prin-

5 ciple of operation of my invention, together with the apparatus which I now consider to represent the best embodiment thereof, but I desire to have it understood that the apparatus shown is only illustrative, and that the invention can be carried out by other means.

- 10 What I claim as new and desire to secure by Letters Patent of the United States, is:—
- 10 1. In an internal combustion engine, the combination of an air starting valve, a cam shaft, a cam thereon, means through which the cam actuates the air starting valve, said means including a lever and a roller, and a movable fulcrum for the lever which is moved by starting air to bring the roller into operative relation to the cam.
  - 15 2. In an internal combustion engine, the combination of an air starting valve, a cam shaft, a cam thereon, a lever connected to the

valve, a rod connected to the lever and terminating adjacent the cam, and a movable fulcrum for the lever which is actuated by starting air to move the end of the rod into operative relation to said cam.

25

3. In an internal combustion engine, the combination of an air starting valve, a cam shaft, a cam thereon, a lever connected to the valve, a rod connected to the lever and terminating adjacent the cam, a cylinder, a piston therein, said lever being fulcrumed on said piston, and conduit means for conveying starting air to the air starting valve and to said cylinder so as to move the piston therein and bring the end of said rod into operative relation to the cam when air is admitted to start the engine.

In witness whereof, I hereunto set my hand this 10th day of Sept. 1918.

OTTO F. PERSSON.
